[57] CLAIM

The ornamental design of a tooth for a power digger, as shown and described.

DESCRIPTION

FIG. 1 is a top perspective view showing the front and right side of the tooth for a power digger according to my new design;

FIG. 2 is a right side elevational view thereof, the left side elevational view being a mirror image;

FIG. 3 is a front elevational view thereof;

FIG. 4 is a top plan view thereof;

FIG. 5 is a rear elevational view thereof;

FIG. 6 is a bottom plan view thereof; and,

FIG. 7 is a bottom perspective view showing the rear and right side thereof.

FIG. 1

FIG. 2

FIG. 3

FIG. 4

FIG. 5

FIG. 6

FIG. 7
